UNITED STATES PATENT OFFICE.

HENRY A. CHRISTY, OF KENILWORTH, ILLINOIS, ASSIGNOR TO AMERICAN CAR ROOF CO., OF CHICAGO, ILLINOIS, A CORPORATION OF ILLINOIS.

DRAFT-GEAR.

1,165,752.

Specification of Letters Patent. Patented Dec. 28, 1915.

Application filed June 30, 1915. Serial No. 37,167.

To all whom it may concern:

Be it known that I, HENRY A. CHRISTY, a citizen of the United States, residing at Kenilworth, in the county of Cook and State of Illinois, have invented certain new and useful Improvements in Draft-Gears, of which the following is a specification.

The invention illustrated, described, and claimed in this application, relates to the draft-gears or draft-riggings of railway-cars and pertains more particularly to structures of this general character equipped with friction shock-absorbing means.

One of the salient features of the invention is the provision of means of such kind that, the wear of the friction elements does not take place on the housing proper, so that the latter is not subjected to being worn out from such causes.

A further object of the invention is to increase the friction between the parts as they move, and, in the preferred embodiments of the invention set forth herein, this is accomplished by means of a wedge acting upon a rocking-member to increase the pressure of the latter on a suitable wear-block which, as it becomes worn, may be backed up for further service and which may be readily replaced when fully worn out.

Having these objects in view it should be borne in mind that the preferred embodiments of the invention described below are illustrated in the accompanying drawing forming a part of this specification and throughout the various views of such drawing like reference characters refer to the same parts.

To those skilled in this art it will be clear that the above-mentioned aims and purposes as well as others are fulfilled in the employment of devices of this character.

In the drawing: Figure 1 is a horizontal section through a draft-rigging incorporating one form of device embodying this invention; Fig. 2 is a similar view of another desirable embodiment of the invention; and Fig. 3 illustrates in section a fragment of the housing having the bearing or wear block cast integral therewith.

Referring first to the structure depicted in Fig. 1, it will be observed that this illustration shows a fragment of a coupler-shank 10 and its associated strap or yoke 11. Forward and rear draft-sill stops 12, 12, and 55 13, 13, respectively, are also shown.

Coöperating with the stops 12, 12, is a cast-metal casing or housing 14 having lugs, flanges, or ears 15, 15, adapted under normal conditions to bear against the front draft-sill stops 12, 12, as shown. This housing has a portion 16 of reduced cross-section accommodating an outer compression-spring 17 and a similar smaller inclosed spring 18.

The inner part of the housing is somewhat enlarged at 19 and receives two opposed wear-blocks 20 and 21, each beveled at its inner end at 22 and 23 respectively. Bearing against the other stops is the usual follower 24 which coöperates with the yoke 11 and in front of the follower is a pair of companion wedges 25 and 26 each with wedge surfaces 27 and 28, and 29 and 30 respectively. Accommodated between the springs, the wear-blocks, and the wedges, 75 31 and 32 are a pair of members 31 and 32 beveled at 33 and 34 and adapted to rock on one another by means of an interposed fulcrum-pin 35 received in substantially semi-cylindrical cavities 36 and 37 in the adjacent 80 faces of such members. The rear ends of the springs 17 and 19 bear directly against these blocks or elements and the rear ends of the latter in turn may, under the condition shown in Fig. 1, bear against the front 85 face of the follower 24. In this particular embodiment of the invention the co-acting faces 38 and 39 of the wear-blocks and 40 and 41 of the pivoted members are substantially parallel to the axis of the appliance as a whole.

The operation of this improved and novel appliance occurs practically as follows: Assuming that the coupler is drawn forwardly, that is, to the left, as the parts are viewed 95 in Fig. 1, the yoke 11 and the follower 24, of course, travel with it, the latter leaving the stops 13 and pushing the wedges 25 and 26 forwardly, these in turn forcing the members 31 and 32 forwardly against the action 100

of the springs. Owing to the angles of the various surfaces of these coöperating parts, the members 31, and 32 will travel more rapidly than the wedges 25 and 26. It will also be noted that as the wedges advance they also travel inwardly laterally toward one another owing to their co-action with the fixed beveled surfaces 22 and 23. Such movement of the parts causes a slight rocking of the elements 31 and 32 on their common fulcrum-pin tending to separate their forward ends, in this way increasing their pressure on the wear-blocks 20 and 21, it being understood that the surfaces 40 and 38 and 41 and 39 slide on one another, the friction between the various parts acting as a shock absorber substantially without recoil. It should be clear that each of the parts 25 and 26 has a friction travel on the follower 24, on the corresponding wear-block, and on the respective rocking member; also that the pair of rocking elements have a direct friction bearing on the faces of the wear-blocks. As these blocks 20 and 21 become worn they may be shimmed out or backed up so as to stand up to the work and if they become unduly worn they can be readily replaced at small expense. Stated differently, no wear occurs on the housing itself so that the latter does not require replacement. The provision of these two members 31 and 32 capable of rocking on one another permits an increase of the pressure which such members exert on the wear-blocks, and, owing to their pivotal connection they can compensate for any inequalities or imperfections in the foundry casting of the various parts. Upon release of the strain on the coupler, the lateral pressure of the parts 31 and 32 on the wear-blocks decreases, the springs expand, and the various elements are automatically restored to their original positions, all as will be readily understood.

In case the coupler is pushed inwardly instead of pulled outwardly as explained above, then the follower 24 will remain stationary and the inward travel of the coupler will force the housing and its springs inwardly, the parts coöperating to absorb the shock in practically the same manner as outlined above, the relative travel of the members being substantially the same as when the coupler is pulled outwardly.

In Fig. 2 a somewhat modified construction is shown and in this instance the wear-blocks 50 and 51 are of the same general conformation as those shown in Fig. 1, but have in addition the enlargements 52 and 53 which make their beveled surfaces 54 and 55 of somewhat greater extent. The companion rocking-members 56 and 57 have their rear ends reversely beveled at 58 and 59 and their front ends are correspondingly beveled at 60 and 61 so that each member constitutes a double wedge and the two combined form

a split double-ended wedge. Between the members 56 and 57 and the corresponding pressure-blocks 51 and 50 I interpose the beveled blocks or intermediate members 62 and 63 adapted to travel on the faces of the wear-blocks and beveled at 64 and 65 to conform to the surfaces 60 and 61. This appliance works on substantially the same principle as that shown in Fig. 1, excepting that the pivoted members instead of bearing directly on the wear-blocks do so through the intermediate members 62 and 63.

While I have herein shown two desirable embodiments of the invention, it should be understood and appreciated that many minor mechanical changes may be made in these structures without departure from the substance of the invention and without the sacrifice of any of its real benefits and advantages. It will be clear that if preferred, the wear-blocks may constitute integral portions of the housing instead of separate elements. This style of structure is shown in Fig. 3, the housing being characterized 16^a and the wear part 20^a.

I claim:

1. In a railway-car draft-gear, the combination of a housing adapted to be operatively associated with draft-sill stops and a friction appliance including, a wear-block in and adapted to travel with said housing, a wedge adapted to coöperate with the opposed draft-sill stops, and a pivoted member coöperating with said wedge and wear-block, whereby relative travel of the parts causes the wedge to increase the pressure of the member on the wear-block, substantially as described.

2. In a railway-car draft-gear, the combination of a housing adapted to be operatively associated with draft-sill stops, a spring in said housing, and a friction appliance including a wear block in and adapted to travel with said housing, a wedge adapted to coöperate with the opposed draft-sill stops, and a pivoted member acted upon by said spring and co-acting with said wedge and wear-block, whereby relative travel of the parts against the action of said spring causes the wedge to increase the pressure of said pivoted member on the wear-block, substantially as described.

3. In a railway-car draft-gear, the combination of a housing adapted to be operatively associated with draft-sill stops, a cushion in said housing, and a friction appliance including a wear block in and adapted to travel with said housing, a wedge adapted to coöperate with the opposed draft-sill stops, and a pivoted member acted upon by said cushion and co-acting with said wedge and wear-block, whereby relative travel of the parts against the action of said cushion causes the wedge to increase the pressure of said pivoted-member on the wear-block.

wear-block, said cushion constituting the sole cushioning means for the appliance, substantially as described.

4. In a railway-car draft-gear, the combination of a housing adapted to be operatively associated with draft-sill stops, and a friction appliance including a beveled wear-block in said housing, a wedge adapted to coöperate with the opposed draft-sill stops, a beveled pivoted member co-acting with said wedge and wear-block, the wedge being accommodated between the beveled face of the wear-block and the beveled face of the pivoted member, whereby relative travel of the parts causes the wedge to increase the pressure of said pivoted member on the wear-block, substantially as described.

5. In a railway-car draft-gear, the combination of a housing adapted to be operatively associated with draft-sill stops, a cushion, and a friction appliance including a beveled wear-block in and adapted to travel with said housing, a wedge adapted to coöperate with the opposed draft-sill stops, and a beveled pivoted member co-acting with said wedge and wear-block, the wedge coöperating with the beveled face of the wear-block and member, said cushion opposing the travel of the pivoted member on the wear-block, whereby relative travel of the parts causes the wedge to increase the pressure of said pivoted member on the wear-block, substantially as described.

6. In a railway-car draft-gear, the combination of a housing adapted to be operatively associated with draft-sill stops, a pair of wear-blocks in and adapted to travel with said housing, a pair of wedges adapted to coöperate with the opposed draft-sill stops, a pair of members adapted to rock on one another and co-acting with said wedges and wear-blocks, whereby relative travel of the parts causes the wedges to increase the pressure of said pivoted members on the respective wear-blocks, substantially as described.

7. In a railway-car draft-gear, the combination of a housing adapted to be operatively associated with draft-sill stops, a pair of wear-blocks in and adapted to travel with said housing, a pair of wedges adapted to coöperate with the opposed draft-sill stops, a pair of members adapted to rock on one another interposed between said wedges and adapted to travel relatively to said wear-blocks, whereby relative travel of the parts causes the wedges to increase the pressure of said pivoted members on the respective wear-blocks, substantially as described.

8. In a railway-car draft-gear, the combination of a housing adapted to be operatively associated with draft-sill stops, a pair of beveled wear-blocks in said housing, a pair of wedges adapted to coöperate with the opposed draft-sill stops, a pair of bevel-

ed members adapted to rock on one another and co-acting with said wedges and wear-blocks, the wedges acting upon the beveled faces of said wear-blocks and pivoted members, and cushion means interposed between said housing and pivoted members, whereby relative travel of the parts causes the wedges to increase the pressure of said pivoted members on the wear-blocks, substantially as described.

9. In a railway-car draft-gear, the combination of a housing adapted to be operatively associated with draft-sill stops, and a friction appliance including a wear-block in said housing, a wedge adapted to coöperate with the opposed draft-sill stops, a double-wedge member co-acting with said wedge, and an intermediate pressure-transmitting member interposed between said double-wedge member and said wear-block, whereby relative travel of the parts causes the wedge to increase the pressure of said intermediate member on the wear-block by means of double-wedge member, substantially as described.

10. In a railway-car draft-gear, the combination of a housing adapted to be operatively associated with draft-sill stops, and a friction appliance including a wear-block in said housing, a wedge adapted to coöperate with the opposed draft-sill stops, a pivoted double-wedge member co-acting with said wedge, and an intermediate pressure-transmitting member interposed between said double-wedge member and said wear-block, whereby relative travel of said parts causes the wedge to increase the pressure of said intermediate member on the wear-block by means of said pivoted member, substantially as described.

11. In a railway-car draft-gear, the combination of a housing adapted to be operatively associated with draft-sill stops, a pair of wear-blocks in said housing, a pair of wedges adapted to coöperate with the opposed draft-sill stops, a double-ended wedge member co-acting with said wedges and composed of two parts adapted to rock on one another, and intermediate pressure-transmitting members interposed between said double-wedge member and said wear-blocks, whereby relative travel of the parts causes the wedges to increase the pressure of said intermediate members on the wear-blocks by means of the double-wedge member, substantially as described.

12. In a railway-car draft-gear, the combination of a housing adapted to be operatively associated with draft-sill stops, a pair of beveled wear-blocks in said housing, a pair of wedges adapted to coöperate with the opposed draft-sill stops, a double-ended wedge member co-acting with said wedges and composed of two members adapted to

rock on one another, and a pair of intermediate beveled pressure-transmitting members interposed between said double-wedge member and said wear-blocks, whereby the 5 coöperation of the wedges with the beveled faces of the wear-blocks and the double-wedge member increases the pressure of said

intermediate members on said wear-blocks by means of said double-wedge member which co-acts with the beveled surfaces of 10 such intermediate members, substantially as described.

HENRY A. CHRISTY.
